(57) **CLAIM**

The ornamental design for a brush, as shown and described.

DESCRIPTION

FIG. 1 is a top perspective view of a brush showing my new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof; and,

FIG. 7 is a rear elevation view thereof.

The dashed broken lines in the drawings illustrate portions of the brush that form no part of the claimed design. The dot-dash broken lines in the drawings define the boundaries of the claimed design and form no part thereof.

1 Claim, 6 Drawing Sheets
